CHARLES MORGAN OLMSTED, OF PASADENA, CALIFORNIA.

AERIAL TOY.

1,138,401.

Specification of Letters Patent.

Patented May 4, 1915.

Application filed October 2, 1909. Serial No. 520,678.

To all whom it may concern:

Be it known that I, CHARLES M. OLMSTED, of Pasadena, in the county of Los Angeles and State of California, have invented certain new and useful Improvements in Aerial Toys; and I do hereby declare the following to be a full, clear, and exact description of the invention, such as will enable others skilled in the art to which it appertains to make and use the same.

In Letters Patent No. 1,019,078 I have disclosed how to construct the blades of an aerial propeller to obtain maximum power under minimum energy. The idea there 15 present may be employed in a toy or flying top.

The object, therefore, of the present invention is to provide a simple and highly interesting flying top capable of being 20 easily set in motion and of rising to a great height or traveling a considerable distance.

The invention will be hereinafter fully set forth and particularly pointed out in the claims.

25 In the accompanying drawings, Figure 1 is a view in side elevation. Figs. 2 and 3 are top and bottom plan views of the flying top. Fig. 4 is an enlarged cross sectional view of the ring or fly-wheel. Fig. 5 is a similar 30 view showing a slight modification. Fig. 6 shows a device which may be used in projecting the top. Fig. 7 is a transverse sectional view. Fig. 8 is a section on line 8-8, Fig. 2.

35 Referring to the drawings, 1, 1, designate two blades which are shown as united at their inner ends, and 2 is a ring or fly-wheel to which the blades are secured at their outer ends. This ring, in cross section, is 40 either circular, as shown in Fig. 4, or elliptical, with the major axis of the ellipse perpendicular to the plane of the ring as shown in Fig. 5. This ring or fly wheel is of such a weight that the radius of gyration of the 45 flying part is at least greater than 58%, and preferably greater than three fourths ($\frac{3}{4}$) of the peripheral radius of the flying part.

Each of the blades is, preferably, made 50 from thin metal and after the manner contemplated by my above noted application for patent; that is, each blade is widened near its base; is of concavo-convex formation; has a helical twist; and tapers from its widened portion to its outer end where 55 it is united to the encircling ring or fly-

wheel. The total width of the blades gradually increases from the base toward the periphery until a maximum is reached at a distance from the axis where the pitch angle of each blade is not less than forty-five degrees, and then gradually decreases from this point outward. In other words, each blade has a widened portion 3 of concavo-convex formation in addition to a helical twist, although it may be flat and twisted helically as pointed out in my above noted application for patent, and this widened portion, which is bent so as to begin to coincide with the helix as near to the axis as is practical, gradually increases in width 60 until it attains a maximum width where the pitch angle is about forty-five degrees or more. From this point the blades are gradually lessened in width, with the result that more than one-half the blade surface lies within a circle concentric with the fly wheel and having approximately one-half its diameter. Each blade is shown as being concaved on its underside, and the depth of the concavity at any point is equal 65 to about one-fifteenth of the width of the blade over most of its extent, but this depth is proportionately greater near the axis of the propeller where some of the blade has been cut away to make room for a spinning spool. Theoretically the pitch should be the same throughout the whole blade and the width of the blades should everywhere be 70 determined by the equations set forth in the aforesaid application for patent, but for 75 certain practical reasons, such as stamping the propeller out of one piece of metal, and the necessity of leaving space for the centering hole and spinning tool, the purely theoretical case may be departed from more 80 or less near the axis without appreciably 85 lessening the efficiency of the blade. Further reference to the rules which attain in 90 forming the blades is unnecessary in this 95 case.

I have shown the widest portions of the blades intersecting the plane of the fly-wheel and extending some distance below such planes, and while I have found this highly 100 advantageous, yet the invention is not to be restricted in this respect. Better results 105 are secured, however, by having the fly-wheel considerably heavier than the blades and the widest portions of the latter intersecting the plane of the fly-wheel, but if 110

the described manner of forming the blades be observed it is not necessary that their widest portions should intersect the plane of the fly-wheel.

5 In the drawings I have shown but two blades, but any desired number may be used.

At the axis of the top I have formed an opening 4 to receive a centering and directing pin of any suitable means for setting the top in motion by revolving it on its axis. While various means may be employed for this purpose, I have found that shown to be highly advantageous. It embodies a handle 5 from which extends a rod or centering pin 6 whereon is mounted a spool 7 carrying at its outer end two pins 8 which are designed to engage opposite edges of the blades when the top is located on the spool with the centering pin extended through its opening. The spool is readily turned by the unwinding of a cord 9, and as the top attains the necessary velocity it will fly from the spool and being directed by the position of rod 6 will rise into the air to a height of 250 feet or more. If the projecting device be held perpendicularly the top will usually rise on a straight line, and likewise if the handle be inclined the line of travel will be oblique.

30 The manner in which the cord is unwound from the spool is immaterial, but best results are obtained by observing the arrangement shown. Preferably a loop 10 is formed in the free end of the cord and caused to engage a hook 12 projecting from the lower end of the handle, and the unwinding of the cord is facilitated by the employment of a hooked finger-piece 13. The 35 cord may be of any suitable length, and if desired may be passed under the foot of the operator so that by pressing his leg downwardly foot power may be used to unwind the cord from the spool. By means of the 40 hook 12 and the finger piece 13 the speed of the hand is reduced to one-half for a given speed of unwinding the cord, and at the same time the stationary hand is relieved of the twist which it gets when the cord is 45 simply pulled on a straight line in the known way. The method employed for projecting the toy may be varied at pleasure.

The superior flying qualities of the toy are due to a correct proportioning of the 50 weight and diameter of the ring, acting as a fly-wheel, combined with the correct proportioning and shaping of the blades. The weight and diameter of the ring are calculated on the assumption that the person 55 spinning the top is capable of imparting 40 ft. lbs. of energy thereto, the velocity of rotation being taken as the square root of the mean square of all velocities experienced when the top is given 40 ft. lbs. of 60 energy at the start, and the pitch of the 65

blades is preferably about one-third of the circumference of the ring. The value taken for the pitch is more or less arbitrary and depends upon whether extreme height or extreme length of duration of flight is desired. The stated value—one-third the circumference—gives the extreme height when the cross section of the ring is circular.

70 While I have described and shown in the drawings the best means of obtaining the 75 most desirable results, yet I do not confine myself to exact formations, since changes may be made without departing from the scope of the invention.

I claim as my invention:—

80 1. An aerial toy comprising a ring forming a fly-wheel, and a plurality of helically twisted blades radiating from the axis of the ring and secured to the latter at their outer ends, each blade gradually increasing in width from its base and bent or curved transversely, the maximum width being coextensive with a pitch not less than 45°, from which point each blade is gradually decreased in width to its outer ends. 90

2. An aerial toy comprising a ring forming a fly-wheel, and a plurality of helically twisted blades radiating from the axis of the ring and secured to the latter at their outer ends, each blade being of concavo convex formation for a portion or all of its length and of increased width near its base, more than half of the blade surface being within a circle concentric with the fly wheel ring and having approximately 100 half its diameter. 95

3. An aerial toy comprising a ring forming a fly-wheel, and a plurality of helically twisted blades radiating from the axis of the ring and secured to the latter at 105 their outer ends, each blade gradually increasing in width from its base and concaved on its underside for a portion or all of its length, the maximum width being coextensive with a pitch of about 45° or more 110 from which point each blade is gradually decreased in width to the periphery of the toy. 110

4. An aerial toy comprising a ring forming a fly-wheel, and a plurality of helically twisted blades radiating from the axis of the ring and secured to the latter at their outer ends, the weight of the fly-wheel being greater than that of the blades, 115 said blades being bent or curved and concaved on their undersides and of gradually increasing width from the axis of the ring to a point coextensive with a pitch of about 45° or more of the concaved portion, such widened portions of the blades intersecting 120 the plane of the ring. 125

5. An aerial toy comprising a flying part having a plurality of radiating blades, the latter having more than half of the blade surface within a circle the radius of which 130

is one half as great as the extreme radius of the flying part, said blades being weighted at their outer ends, and being twisted so that the pitch angle of the wide bases is at least twice as great as the pitch angle of the narrow tips.

6. An aerial toy comprising a plurality of helicoidally twisted blades radiating from a center and weighted at their outer ends, each blade being of concavo-convex formation for a portion or all of its length and of increased width near its base, more than half of the blade surface being within a circle concentric with the radiating blades 10 and having a diameter half as great as the diameter of the circle described by the extreme tips of the blades when the toy is 15 spinning.

7. An aerial toy comprising a plurality of helicoidally twisted blades radiating from 20 a common axis, each blade gradually increasing in width from its base and bent or curved transversely, the maximum width being co-extensive with a pitch not less than 25 45°, from which point each blade is gradually decreased in width to its outer end, said blades being weighted at their outer ends.

In testimony whereof, I have signed this specification in the presence of two sub- 30 scribing witnesses.

CHARLES MORGAN OLMSTED.
